UNITED STATES PATENT OFFICE.

ENOCH GEORGE, JR., OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA.

DRAFT-RIGGING.

1,362,691.

Specification of Letters Patent. Patented Dec. 21, 1920.

Application filed August 8, 1919. Serial No. 316,112.

To all whom it may concern:

Be it known that I, ENOCH GEORGE, Jr., a citizen of the United States, residing at Pittsburgh, in the county of Allegheny and 5 State of Pennsylvania, have invented certain new and useful Improvements in Draft-Rigging; and I do hereby declare the following to be a full, clear, and exact description of the invention, such as will enable 10 others skilled in the art to which it appertains to make and use the same.

My invention relates to the construction of draft rigging for railway cars, and particularly to the character of connection between the coupler and the draft yoke. The 15 primary object of the invention is to provide simple and efficient means for pivotally connecting the car coupler and yoke in a manner obviating the disadvantages incident to the use of the well known tail pin that is commonly employed for that purpose, such disadvantages being generally due to loss or looseness of the key, nut or other retaining device of the tail pin resulting 20 in the distortion or fracture of the pin, a result which is promoted by the spreading of the arms of the ordinary wrought iron yoke consequent upon the loss or improper adjustment of the said retaining device.

Generally stated the invention involves 30 the employment of a draft yoke or draft member having at one end an integral hood encircling the rear end of a car coupler and provided with oppositely disposed pivot pins projecting toward the center of the hood and separated at their adjacent ends, in combination with a car coupler which is provided at its rear end with a plurality of arms extending into the interior of the hood 35 and having a filler member interposed between the said arms and also extending into the hood, the arms of the coupler being provided with openings or recesses for receiving the respective pivot pins and the filler member constituting means for maintaining 40 the assembled relation of said arms and pivot pins.

In the drawings illustrating the invention, the scope whereof is pointed out in the 45 claims,

Figure 1 is a plan view of a draft rigging embodying the invention, the forward portion of the car coupler being omitted.

Fig. 2 is a side elevation of the construction shown in Fig. 1.

Fig. 3 is a detail vertical section of the construction illustrated in Figs. 1 and 2.

Fig. 4 is a detail horizontal section on the line 4—4, Fig. 3.

Fig. 5 is a detail plan view of the connected ends of a car coupler and draft yoke embodying a modified form of my invention.

Fig. 6 is a detail view corresponding to Fig. 3, but illustrating the modification shown in Fig. 5.

Fig. 7 is a detail vertical section of the connected ends of a coupler and draft yoke, showing how the construction illustrated in Figs. 5 and 6 may be converted into a form 70 of pivotal connection of the type exemplified in Figs. 1 to 4 inclusive.

Fig. 8 is a bottom plan view of the construction shown in Fig. 7.

Fig. 9 is a view corresponding to Fig. 7, 75 but illustrating the construction shown in Figs. 5 and 6 as converted to allow a single pin to be employed as a pivot.

In the drawings, 1 is the car coupler and 2 is a draft member that is pivotally connected thereto. The draft member 2 is preferably in the form of a yoke having upper and lower arms 3 which are rigidly united at their rear ends by a tie bar 4 and at their forward ends by an integral hollow hood 80 5 which is adapted to receive the rear end of the coupler 1. The space or opening 6 to the rear of the hood 5 between the yoke arms 3 is adapted to receive the usual or any desired form of cushioning unit (not 85 shown).

The hood portion 5 of the yoke is provided with a plurality of inwardly extending preferably cylindrical pivot pins 7 whose axes are in alinement and whose adjacent ends are spaced from each other. These pivot pins may be, and preferably are, fitted in corresponding recesses or sockets 8 formed in the hood as such a construction permits them to be readily renewed when 90 100

worn or if broken; but, as shown at 7^a, in Figs. 5 and 6, they may be formed integral with the hood.

The side walls 9 of the hood 5 preferably 5 flare or diverge both in front of and to the rear of the pivot pins 7, thereby providing for a wide range of lateral swinging of the coupler 1 without unduly increasing the width of the hood.

10 The coupler is provided with a plurality of arms 10 having openings or recesses 11 therein corresponding to and adapted to receive the respective pivot pins 7. These arms are maintained in assembled relation to the 15 pivot pins 7 by means of an interposed filler member 12 which is preferably secured in position by means of rivets 13.

In the construction shown in Figs. 5 and 6 20 the pivot pins 7^a are formed integral with the hood 5^a of the yoke 2^a instead of being detachably mounted thereon. The filler member 12^a which is interposed between the arms 10^a of the coupler to maintain the latter in assembled relation to the pivot pins 25 7^a may be secured in position by a rivet 13^a passing through the arms 10^a. The construction shown in Figs. 5 and 6 is otherwise the same as the form of the invention first described.

30 In assembling the construction illustrated in Figs. 1 to 4 inclusive, the rear ends of the arms 10 of the coupler are inserted in the hood portion 5 of the yoke 2, the pivot pins 7 are then inserted in the hood one at a time 35 and entered in the corresponding openings 11 of the coupler and sockets 8 of the yoke, and the filler block 12 is thereafter inserted between the arms 10 of the coupler and secured in place.

40 In assembling the construction shown in Figs. 5 and 6 the arms 10^a of the coupler 1^a are successively inserted in the hood 5^a of the yoke and placed in position on their respective pivot pins 7^a, after which the filler 45 member 12^a is secured in position between the arms 10^a.

On its under side and in alinement with the pivot pins 7^a the hood 5^a of the yoke 2^a is preferably formed with a flanged bracket 50 14 supporting a detachable plate 15 which is secured in position by a cotter pin 16. Should the pivots 7^a be broken the yoke 2^a may be utilized by drilling a suitable hole 17 through the bottom of the yoke and partly 55 through the top of the yoke at 17^a, and by employing separable pivot pins 7^b for connecting the yoke to the arms 10^a of the coupler, as shown in Figs. 7 and 8, the plate 15 serving to retain the lower pivot member 60 7^b in place.

In case it is desired to employ a single pivot pin or tail pin 18 instead of using separate pivot pins 7^b to effect a repair when the integral pivots 7^a have been broken, this 65 may be done, as shown in Fig. 9, by drilling

a hole through the filler block 12^a in addition to drilling holes 17 and 17^a in the yoke 2 as heretofore described.

I claim:

1. In a draft rigging, the combination of 70 a draft member having at one end an integral hood portion adapted to encircle the rear end of a car coupler, a plurality of pivot pins within said hood, said pins arranged in axial alinement and spaced apart at their inner ends, a car coupler provided at its rear end with a plurality of arms, and a filler member interposed between said arms, said arms being respectively provided with recesses receiving said pivot pins, and said 75 filler member constituting means for maintaining the assembled relation of said arms and pivot pins.

2. In a draft rigging, the combination of 80 a draft yoke having an opening adapted to receive a cushioning unit and having at its forward end an integral hood portion adapted to encircle the rear end of a car coupler, oppositely extending pivot pins within said hood, said pins spaced apart at 85 their inner ends, a car coupler provided at its rear end with a plurality of arms, and a filler member interposed between said arms and extending between said pivot pins, said arms being provided with recesses receiving 90 said pivot pins.

3. In a draft rigging, the combination of 95 a car coupler and a draft member connected thereto, one of said members having an integral hood portion adapted to encircle the 100 end of the other of said members, and the other of said members being provided at one end with a plurality of arms extending into said hood, a plurality of axially alined pivot pins within the hood said pins being 105 spaced apart at their inner ends, and a filler member interposed between said arms, said arms being provided with recesses receiving said pivot pins.

4. In a draft rigging, the combination of 110 a draft yoke having an opening adapted to receive a cushioning unit and having at its forward end an integral hood portion adapted to encircle the rear end of a car coupler provided on its interior with oppositely disposed sockets adapted to receive spaced pivot pins, alined pivot pins within the hood said pins being spaced at their adjacent ends, and a car coupler provided at its rear end with a plurality of arms extending into 115 said hood, and a filler member interposed between said arms and engaging said pivot pins to retain them in said sockets, said arms being provided with openings respectively adapted to receive said pivot pins. 120

5. In a draft rigging, the combination of 125 a coupler member having a bifurcated rear end, a yoke member having at its front end an integral hood adapted to encircle the bifurcated rear end of the coupler and having 130

an opening to admit of the introduction of
said rear end of the coupler member within
the hood of the yoke, pivot members ar-
ranged in vertical alinement within the hood
5 of the yoke and spaced apart at their adja-
cent ends, one of the first named members
having openings for the reception of the

pivot members, and a filler member inserted
in the bifurcation at the rear end of the cou-
pler between the adjacent ends of aligned 10
pivot members within the hood of the yoke
member.

In testimony whereof I affix my signature.

ENOCH GEORGE, JR.
